United States Patent Office

Des. 202,891
Patented Nov. 16, 1965

202,891

COMBINED TAPE CUTTER AND BLADE THEREFOR

John R. Holthaus, 216 Warren Ave., Baltimore, Md.

Filed Nov. 17, 1964, Ser. No. 82,659

Term of patent 14 years

(Cl. D22—3)

FIG. 2

FIG. 3

FIG. 4.

FIG. 1 is a side elevational view of a combined tape cutter and blade therefor showing my new design;

FIG. 2 is a bottom plan view thereof;

FIG. 3 is an enlarged cross-sectional view taken on line 3—3 of FIG. 1; and

FIG. 4 is a perspective view of the combined tape cutter and blade therefor of FIG. 1.

I claim:

The ornamental design for a combined tape cutter and blade therefor, as shown.
